AYLMER AUGUSTUS LIARDET, OF BRADFORD, AND FREDERICK WILLIAM BERK, OF HARROGATE, ENGLAND.

HOISTING GEAR.

Application filed September 13, 1922. Serial No. 587,923.

To all whom it may concern:

Be it known that we, AYLMER AUGUSTUS LIARDET and FREDERICK WILLIAM BERK, subjects of the King of Great Britain and Ireland, residing at Vulcan Iron Works, Bradford, Yorkshire, England, and 22 Studley Road, Harrogate, Yorkshire, England, respectively, have invented new and useful Improvements in and Relating to Hoisting Gears, of which the following is a specification.

This invention relates to improvements in hoisting gear of that kind in which the winding drum is operated through epicyclic or like gearing and in connection with which two brakes are used to manipulate the load, and it is our object to arrange, construct and combine certain mechanism and gear operable by power whereby the load, load container or load supporter or like is lifted from one level to another and held in the lifted position. The load container or supporting device is allowed to return by gravity without reversing the direction of the driving shaft. The brakes are operated by one lever which merely relieves the brakes and on release of the lever the brakes are automatically applied. In power operation, it is desired to avoid complications and permit the operating shaft to run constantly in one direction whatever the movement of the load, its container, or supporting device.

Broadly the machine comprises, a drum or drums in connection with which operate the hoisting ropes, wires or chains: a planet or other suitable epicyclic gear, and two brakes or brake members acting upon members of the epicyclic train or parts directly connected with such members all arranged so that by operation of the main or power shaft in one direction and the co-operation of the braking members to operate which only one lever is required and the brakes are automatically applied, the load or like will be first lifted, then held and finally allowed to return by gravity. The purposes to which the invention may be applied are many, such for example as crane work, charging machines for cupolas or the like.

We have previously designed and patented in Great Britain under Number 135358 means and apparatus relating to drop ham-

mers wherein we used duplicate brake mechanism and epicyclic gear such mechanism being as it were integral with the drop hammer mechanism. The present invention is in connection with other hoisting gear and, as hereinbefore broadly set out, is capable of either hand or power operation.

In describing our invention in detail reference is made to the accompanying sheet of drawings, similar letters indicating similar parts, in which:—

Fig. 1 represents a sectional elevation of a power operated gear.

Fig. 2 represents an end view.

Fig. 3 represents a detail and connection to the control lever.

For a power-driven apparatus as illustrated herein, A is a countershaft mounted for rotation in bearings carried by standards B, said shaft being adapted to receive motion from a power shaft A^x (Fig. 2) driven by a motor or other suitable means. If a motor is used the connections are simple and only one switch to put the motor into or out of action is required. The shaft A^x will carry a pinion A⁴ (or otherwise be arranged to transmit motion to the shaft A) gearing with a gear wheel A⁵, and on the shaft A^x will be mounted a disc or like D⁵ having a brake band D⁸ on or in connection with its rim D⁹. This disc will be mounted free to revolve on the shaft A and will carry on a pin D⁴ a gear wheel D³ which will mesh with teeth D² on the disc D¹ also mounted loosely on shaft A. The gear or planet wheel D³ will also mesh with a pinion D⁷ fast on shaft A. The disc D¹ will carry a brake D⁹ and the disc D⁵ will carry a pinion D¹⁰ which will engage a gear wheel on a shaft D^x carrying the winding drum D.

The brake bands D⁸ and D⁹ will be arranged substantially as shown in Fig. 2 D⁸ being adjustably connected or anchored at one end F and at the other end F' connected to a weight lever L pivoted at L'. The other brake band D⁹ will be anchored as at F² at one end and at the other end be connected to a lever or like F³ carried from what may be termed the operating shaft G. This shaft will also carry a rocking member G' with rollers or like bearings against which the lever L will bear.

In Fig. 2, the mechanism is shown in the middle or neutral position, the brake D^8 being on and the brake D^9 off. Now if the rocking member G' be moved clockwise the 5 effect will be to lift the lever L and release the brake D^8 . The same movement will lower the lever F^3 and apply the brake D^9 . If however the member G' is moved in the opposite direction, the lever L will still be 10 lifted and the brake D^8 released, but in this case the lever F^3 will rise and further release the brake D^9 . The shaft G by links, levers, rods or the like will be arranged in, connection with a suitable operating handle H^* 15 Fig. 3.

The drum D will carry the hoisting chain, ropes or the like. To operate, the shaft A^* is rotated in one direction and by means of gearing such as before described transmits 20 motion to the shaft A and with the member G' in the neutral position the disc D^5 held, the pinion D^7 will merely transmit motion to the pinion D^3 and through it to the disc D' and no motion will be transmitted to the winding drum. If however the 25 brake D^8 be released by the movement of the shaft G and member G' , say clockwise, the disc D' will be held and the gear will cause the disc D^5 to be rotated and communicate motion to the drum D and the hoisting operation will be carried on until the member G' is returned to its neutral 30 position.

In this position the shaft A will continue 35 running and the bucket is held in its raised position by the brake D^8 . An anti-clockwise movement of the shaft G will merely

further loosen the brake D^8 and at the same time release the brake D^9 , allowing the bucket or load container to return by gravity 40 to its lowest position.

What we claim as our invention is:—

A hoisting apparatus comprising, in combination, a constantly rotating countershaft, a driven shaft adapted to receive motion 45 from said countershaft, a pair of brake drums loosely mounted on said countershaft, gearing between one of said drums and said driven shaft for transmitting motion to the latter, epicyclic gearing between said countershaft and one of said drums for transmitting motion to the drum, the planet pinions of said epicyclic gearing being carried by the other drum, a brake band encircling each of said drums, a weighted lever 50 automatically operative for retaining one of said brake bands in frictional contact with its drum thereby to retain the driven shaft against rotation, and a rock shaft adapted when rocked in one direction to operate 55 said weighted lever thereby to release said brake band and simultaneously tighten the other brake band on its drum and when rocked in the opposite direction to release 60 both of said brake bands thereby to permit rotation of the driven shaft independently 65 of the countershaft.

In testimony whereof we have signed our names to this specification.

AYLMER AUGUSTUS LIARDET.
FREDERICK WILLIAM BERK.
